UNITED STATES PATENT OFFICE

JOHN ZIMMERMANN, JR., OF OAK LANE, PENNSYLVANIA

DOUBLE-PILE FABRIC

Application filed November 12, 1929. Serial No. 406,555.

My invention relates to double pile fabrics, that is to say, to fabrics which are woven with two ground weaves, having pile forming warps extending therebetween which are subsequently cut for the purpose of producing two separate fabrics, each having a pile face.

The original method of weaving cut pile fabrics adapted for use as carpets consists in the temporary insertion in the weave, of wires over which pile loops are formed, which loops are subsequently cut, either prior to or upon the withdrawal of the wires. This method, however, while still extensively used, is largely limited in its application to relatively narrow fabrics, and is not always practical for use in making seamless room size rugs, by reason of the difficulty of inserting and removing the wires in weaves of greater width.

Another method consists in the weaving of two fabrics face to face, which are subsequently cut apart to form the pile. This method dispenses with the use of wires and permits the production of rugs which are limited in their width only by the width of the loom. In the weaving of such fabrics, various arrangements have been suggested and used for the disposition in the ground weaves of the dead ends of pile forming warps. In some cases, half of the color ends are carried in one ground weave, and half in the other ground weave. In other instances, a full set of color ends is carried in each ground weave. The making of these various weaves, however, involves more or less complication in the harness for manipulating the various warps.

Another method employed consists in the disposition of all of the color warps in the lower ground weave, the same being carried across to the upper ground weave, and back again, whenever a particular color is called in the pattern. Where this method is employed, it is customary to make the two ground fabrics of materially different qualities as to body, wearing qualities, etc., in some instances the upper fabric being a mere skeleton and entirely discarded, and in other instances the upper fabric being adaptable

for use only for purposes other than as a floor covering.

A considerable demand has recently arisen for the production of seamless pile carpets made in room sizes, in which the pattern appears upon the back of the fabric, in a manner similar to that of the various oriental rugs. Several attempts have been made to accomplish this purpose, and while there have been instances in which the pattern has been carried through to the back of the relatively lighter upper ground weave, and other instances in which the upper and lower ground weaves have been made having similar qualities as to body, etc., these have not been entirely satisfactory, in that the pattern on the back is not sufficiently well defined, and these weaves usually involve, for their production, considerable complication in the harness for the proper manipulation of the color ends.

The principal object of my present invention is to provide an improved double pile fabric which, when cut apart, will produce two rugs or carpets, in which a well defined pattern will appear upon the back similar to oriental rugs or carpets.

A further object of my invention is to provide a fabric of the type aforesaid in which the pile tufts will be securely held in the ground weaves after the said ground weaves are cut apart.

A further object of my invention is to provide a fabric of the type aforesaid, by means of which the two carpets produced will have similar characteristics as to body, wearing qualities, etc., whereby they will be equally salable.

A further object of my invention is to provide a fabric of the type aforesaid, whereby rugs of the larger or room sizes may be more economically produced than heretofore, in which the pattern will appear upon the back of each of said rugs similarly to the hand made oriental rugs.

With the foregoing objects in view, my invention contemplates the provision in a double pile fabric of upper and lower ground weaves, each having corresponding shots of weft between each crossing of the binder

warp; the carrying of the pile forming warp from one ground weave to the other and back again to form the pile; and the disposition of the color warp whereby the pattern will appear upon the back of each ground weave, and will be well defined thereon.

My invention further contemplates the provision of a double pile fabric, of the character aforesaid, which may be expeditiously and economically woven in an ordinary double pile fabric loom, without undue complication of the harness.

The nature and characteristic features of my invention will be more readily understood from the following description, taken in connection with the accompanying drawings forming part hereof, in which:

Figure 1 is a longitudinal sectional view, to a certain extent diagrammatic, of a double pile fabric embodying the main features of my present invention as applied to a two-shot ground weave, that is to say, to a fabric in which two shots of weft are inserted in each ground weave between each crossing of the binder warp thereof; and

Fig. 2 is a similar view illustrating the arrangement in a three-shot ground weave, that is, where three shots of weft are inserted in each ground weave between each crossing of the binder warp thereof.

Referring now more particularly to Fig. 1 of the drawings, in the particular embodiment of my invention therein shown, the double pile fabric comprises two ground weaves, each having pairs of binder warps 1 and 2, and two shots of weft 3 and 4, between each crossing of the binder warp in the upper fabric, and two shots of weft 5 and 6 between each crossing of the binder warp in the lower fabric.

The pattern forming color warp 7 are all primarily carried in the lower fabric, the dead ends thereof being laid in between the inner and outer planes of the weft shots 5 and 6 of said lower fabric.

The upper fabric is provided with a sufficient quantity of stuffer warp 8, which extend between the inner and outer planes of the weft shots 3 and 4, substantially to equal the body of the color ends 7 in the lower fabric.

Whenever a particular color is called in the pattern, the color end corresponding thereto is raised out of the lower fabric, carried across between the two ground weaves, and entirely through the upper fabric, being looped over an outer plane weft shot 3, and then returned to the body of the lower fabric, extending between adjacent weft shots 5 of the lower fabric and between adjacent weft shots 4 of the upper fabric.

Whenever a particular color end is carried over to form the pile as aforesaid, another and different color end is correspondingly interwoven in and out between adjacent weft shots 6 in the outer plane of the lower fabric.

It should here be noted that whenever a change of color occurs in the pile forming warp which extend across from the lower to the upper fabric and back again, a corresponding change in color occurs in the warp ends which are interwoven with the weft shots 6 in the outer plane of the lower fabric.

It will, of course, be understood that any of the color ends which are not used in the pile may be used for the interweaving with the weft shots 6 in the outer plane of the lower fabric, although, for the best effect, colors complementary to those used in the pile will preferably be used for pattern forming on the back of the lower fabric. For example, if red appears in the pile, blue may be used for the pattern forming on the back of the lower fabric.

The weave shown in Fig. 2 is substantially similar to that shown in Fig. 1, except that three shots of weft 9, 10, and 11 are inserted between each crossing of the binder warp in the upper fabric, and correspondingly three shots of weft 12, 13, and 14 are inserted between each crossing of the binder warp in the lower fabric. In all other respects the weaves are similar.

It will be noted that a color end of each set is looped over each weft shot in the outer plane of the upper fabric, while in the lower fabric the color end which forms the pattern on the back thereof is exposed only over alternate weft shots. However, as the exposed color ends on the back of the lower fabric extend a greater longitudinal extent between alternate wefts, the pattern will be well defined on the back of the lower fabric, as well as on the back of the upper fabric.

It will be seen that there is thus provided a double pile fabric adapted to be cut apart to form two rugs or carpets which will have similar characteristics as to body, wearing qualities, etc., and will be equally salable, and upon the backs of each of which a well defined pattern will appear, and that this fabric may be economically produced in an ordinary loom without undue complication of the harness for manipulating the warp.

I claim:

1. A double pile fabric comprising two ground weaves, pattern forming color warp primarily carried in the lower ground weave, the particular color ends appearing in the pile of the fabric extending across from the lower ground weave to the upper and back again, passing entirely through the upper ground weave and being looped over weft shots in the outer plane thereof, and where a particular color end is carried over to form the pile another and different color end being interwoven with the weft shots in the outer plane of the lower ground weave, the color ends which are thus brought out on the back of the lower ground weave being

changed whenever the color ends in the pile are changed.

2. A double pile fabric comprising two ground weaves of similar formation, pattern forming color warp primarily carried in the lower ground weave, the particular color ends appearing in the pile of the fabric extending across from the lower ground weave to the upper and back again, passing entirely through the upper ground weave and being looped over weft shots in the outer plane thereof, and where a particular color end is carried over to form the pile another and different color end being interwoven with the weft shots in the outer plane of the lower ground weave, the color ends which are thus brought out on the back of the lower ground weave being changed whenever the color ends in the pile are changed.

3. A double pile fabric comprising two ground weaves of similar formation, pattern forming color warp primarily carried in the lower ground weave, the particular color ends appearing in the pile of the fabric extending across from the lower ground weave to the upper and back again, passing entirely through the upper ground weave and being looped over weft shots in the outer plane thereof, and where a particular color end is carried over to form the pile another and different color end being interwoven with the weft shots in the outer plane of the lower ground weave, the color ends which are thus brought out on the back of the lower ground weave being changed whenever the color ends in the pile are changed, and the upper ground weave having stuffer warp extending between inner and outer plane weft shots, said stuffer warp being of a quantity to impart substantially the same body to the upper ground weave as is provided by the dead color ends in the lower ground weave.

4. A double pile fabric comprising two ground weaves of similar formation, pattern forming color warp primarily carried in the lower ground weave, the particular color ends appearing in the pile of the fabric extending across from the lower ground weave to the upper and back again, being looped over weft shots in the outer plane of the upper ground weave and extending respectively between adjacent weft shots in both the upper and lower ground weaves, and where a particular color end is carried over to form the pile another and different color end being interwoven with the weft shots in the outer plane of the lower ground weave, the color ends which are thus brought out on the back of the lower ground weave being changed whenever the color ends in the pile are changed.

5. A double pile fabric comprising two ground weaves of similar formation, pattern forming color warp primarily carried in the lower ground weave, the particular color ends

In testimony whereof, I have hereunto signed my name.
